SELF-PROPELLED COMBINE

Robert Ashton, Toronto, Ontario, Canada, assignor to
Massey-Harris-Ferguson Inc., Racine, Wis., a corpora-
tion of Maryland

Application March 26, 1956, Serial No. 40,769

Term of patent 14 years

(Cl. D40—1)

Des. 180,054

PAGE 2

Fig. 3

Fig. 4

Fig. 1 is a left side elevational view of a self-propelled combine embodying my new design;

Fig. 2 is a right side view of the combine shown in Fig. 1;

Fig. 3 is a front view; and

Fig. 4 is a rear view of the combine shown in Figs. 1 and 2.

The characteristic features of the combine reside in the portions shown in full lines.

I claim:

The ornamental design for a self-propelled combine, substantially as shown and described.
